Application February 1, 1932. Serial No. 590,058

6 Claims. (Cl. 113—46)

This invention relates to presses, and more particularly to power presses adapted for drawing or forming sheet metal and the like.

One object of the present invention is the provision of a press having a movable pressure plate which is operated in one direction against a yielding pressure cushion when the movable die comes into engagement with the work, the pressure plate having a lock independent of the pressure cushion for temporarily holding it against return movement during a predetermined part of a cycle of press movements.

Another object of the invention is the provision of a lock of the character described having relatively movable piston and cylinder elements in which liquid is trapped periodically, these elements having an auxiliary pressure device so that the trapped liquid may be subjected to a predetermined pressure in order to compensate for air that might have become trapped in the liquid, or to compensate for any slight lack in filling of the cylinder.

Other objects and advantages of the invention will be apparent from the following description, the appended claims, and the accompanying drawings, in which—

Fig. 1 is a side elevation of a press, shown partly in section on the line 1—1 of Fig. 2 and embodying the present invention;

Fig. 2 is a horizontal section on the line 2—2 of Fig. 1; and

Fig. 3 is a section on the line 3—3 of Fig. 2.

Referring more particularly to the drawings by reference numerals, 10 designates the frame of a power press adapted for drawing or forming sheet metal or the like. In accordance with the present invention the drawing press is of the single action type, the upper part of the press frame rotatably supporting a crank shaft 11 which is connected by cranks 12 to a movable die carrying slide 13 from which the upper die 14 may be supported. The slide 13 is guided for vertical reciprocatory movement in the opposite frame sides.

The die 14 is adapted to cooperate with a lower stationary die 16 supported on the bolster plate 17 which is secured on the press bed 18. A draw ring 19 surrounds the lower die 16, the draw ring cooperating with the outer portions of the top die 14 so that the work or blank of sheet metal 21 will be gripped between these parts when the upper die descends in order to hold the outer edges of the blank under a suitable predetermined pressure preventing buckling or tearing of the sheet during the formation of the finished

article. The draw ring 19 is urged upwardly in a yielding manner during the time the upper die is descending by means of a yielding pressure cushion or cushions provided below the bolster plate. In accordance with the present invention two compressed air cushions are employed to yieldingly resist downward movements of the draw ring. Each embodies telescopically related piston and cylinder members 24 and 25 constituting an air chamber of variable size. The pressure plate 23 forms the top of the cylinder 25 and is guided at opposite sides in the well or opening provided in the press bed. The lower member 24 is fixed in position on a cross plate 26. Movement is transmitted from the pressure plate 23 by means of pins 27 which project through holes in the bolster plate and which rest on the upper side of the pressure plate and support the draw ring at their upper ends.

It will be understood that the pressure cushions are supplied with air under a predetermined pressure, the factory supply line being connected through a pipe 29 to the lower side each of the fixed piston members 24. The pipe 29 may extend centrally across the lower sides of both 80 cushions. The air supplied to the pressure cushions is regulated by a pressure regulating valve 28 which permits flow into the cushion to maintain the air in the cushion up to some predetermined value although movement of the air in a reverse 85 direction, from the pressure cushion toward the supply lines, is prevented by a suitable check valve.

During upward movements of the top die slide, in ordinary constructions now in use, the draw ring follows the upper slide and under certain conditions creates a kick back which has many objections. Means are therefore provided to temporarily hold or lock the pressure plate against return or upward movement during a 95 predetermined part of a cycle of operations so that the draw ring will not be pushed upwardly until after the upper slide has traveled a considerable distance away from the formed article. This lock is preferably constructed independent 100 of the pressure cushion itself and at one side of the pressure cushion. Two such locking devices, as shown, are provided, at opposite sides of each pressure plate, so as to hold the latter in a balanced manner until such time in the 105 cycle as the upward movement of the pressure plate is desired. These locks are of the hydraulic type as they employ oil or other liquid as the locking medium.

The pressure plate lock is provided in the space 110

below a corner of the pressure plate. The lock designated generally 31 which holds one corner of the pressure plate 23 has been shown in section in Fig. 3. 32 is the corner of the pressure plate, in which is fixed a rod 33 which extends downwardly and the lower end of which is fixed to a piston 34 operating in a cylinder 35. The cylinder 35 may be formed as a cylindrical bore in a casting 36 that is mounted securely in the press bed. Adjacent the cylinder 35 is a fluid chamber 38 communicating freely at 39 with the interior of the cylinder. In the chamber 38 is a valve spring 40, adjustably controlled in some suitable manner by an adjusting nut 41, the spring 40 engaging a valve 42 which controls the flow of fluid between the chamber 38 and a pipe 44 which communicates with a reservoir 45 located at any suitable point preferably adjacent to the press and containing a quantity of oil or other suitable liquid 50 under pressure. The valve stem 46 of the valve 42 projects out through a packing member 47 and is adapted to be pushed upwardly by a lever 48 to be more fully described later. In the position of the parts shown in Fig. 3, however, the spring 40 holds the valve head against its seat, trapping the liquid in the cylinder 35 and preventing upward movement of the piston 34. When the valve 42 is opened, the oil or other liquid filling the cylinder 35 is subjected to the pressure of the reservoir 45, and of course when the valve 42 is open the liquid can flow down through the pipe 44 into the cylinder 35 and fill the cylinder as the piston 34 descends. When the valve 42 is closed, with the piston 34 and the pressure plate at the lower ends of their strokes, upward movement of the piston 34 is prevented, since the oil is noncompressible.

It will be understood that the valve 42 is automatically controlled in timed relation to the movements of the press slide. The lever 48 which is engageable with the stem of valve 42 is fixed to a shaft 53, which is operated by a lever 54, moved in turn by a rod 55 which projects upwardly and is pivoted at its upper end to a lever 56 provided on a suitable supporting shaft 58. On the shaft 58 is a lever 59 which is operated by a rotatable cam 60. The cam 60 has a depression 61, and is fixed to the crank shaft 11 so that when the crank is in a position corresponding to the lowermost position of the slide 13, the end of the lever 59 will be down in the depression 61, as shown in Fig. 3. The construction is preferably such that the lever 59 drops into the depression 61 when the crank pin is within about 10° of the bottom of its stroke, and the rise of the cam 60 is such that when the crank pin is rotated to a point about one-half way up on the upward stroke of the slide, the lever 59 will be raised far enough to bring the lever 48 into engagement with and open the valve 42. This permits upward movement of the pressure plate under the influence of the pressure cushion at a time when the upper slide is about one-half way up on its upward stroke, the upward force exerted by the pressure cushion forcing the liquid out of the cylinder 35 through the passage 39 and past the open valve 42, returning into the reservoir. When the slide moves down again the liquid can flow into the cylinder 35. Thus the valve 42 is open until the lowermost position of the pressure plate is almost reached, but at that time the valve 42 closes, the lever 59 dropping into the notch 61

at that point in the cycle of operations and forcing the lever 48 down away from the valve 42.

The shafts 53 are duplicated at the front and rear of the machine, both being controlled at similar times by the same shaft 58. One shaft 80 53 serves as a control for the valves at the rear of the press while the other serves to control the locks at the front.

To compensate for air which may become trapped in the oil or other liquid 50, or to compensate for any slight lack of filling of the cylinder 35, an auxiliary pressure means is provided in order that the trapped liquid in the cylinder 35 may be subjected to a predetermined pressure, maintaining this pressure until the desired time for release of the pressure plate. Thus as shown in Fig. 3, there is a passage 65 communicating with the interior of the cylinder 35 and with a small auxiliary cylinder 66 in which an auxiliary piston or plunger 67 is reciprocably guided. The plunger 67 is the end of a piston rod on which is provided a piston 68, slidably mounted in a cylinder 69, fixed to and preferably forming a part of the casting 36. The piston 68, which may be a great many times larger in diameter than the plunger 67, is subjected to air pressure at a predetermined time in the cycle of operations. One end of the cylinder 69 has a fluid passage 70, extending to a control valve 71. The other end of the cylinder 69 is open to atmosphere through the passage 73. The valve 71 is shown as having a rotatable plug 74 controlled by a lever 75 which is pivoted to the end of an arm 76. Arm 76 is pivoted to a lever 77 provided on the shaft 53 so that the valve 71 will be automatically controlled at about the same time the valve 42 is operated. The valve plug 74 has a series of passages permitting the pipe 70 to be placed in communication either with the exhaust pipe 79 or with the air supply pipe 80 which is preferably a branch 115 from the air supply pipe 29 of the several pressure cushions. Thus when the valve 71 is in the position shown in Fig. 3 the lower side of the piston 68 is subjected to the pressure of the compressed air in the pipe 29, the piston 68 therefore 120 exerting a large pressure upwardly on the plunger 67 and placing the liquid 50 in the hydraulic cylinder under some predetermined definite pressure which will compensate for air that might be trapped in the oil and also for any slight lack of 125 filling in the cylinder 35. The pressure of the oil 50 is maintained until such time until the valve 71 is automatically thrown over to the dotted line position, which takes place at about the same time or preferably just before the valve 42 is 130 opened. Such movement of the valve 71 permits the exhaust of air from the space below the piston 68 out through the exhaust pipe 79, relieving the pressure on the oil 50.

While the form of apparatus herein described constitutes a preferred embodiment of the invention, it is to be understood that the invention is not limited to this precise form of apparatus, and that changes may be made therein without departing from the scope of the invention which is 140 defined in the appended claims.

What is claimed is:—

1. In a press of the character described, a pressure plate, an air cushion below said pressure plate yieldingly resisting the movement of said plate in one direction, and a hydraulic lock independent of said air cushion for temporarily holding said plate against return movement during a predetermined part of a cycle of operation and comprising piston and cylinder elements rela- 150
